US00D702150S

(12) **United States Design Patent**
Pye

(10) **Patent No.:** US D702,150 S
(45) **Date of Patent:** ** Apr. 8, 2014

(54) **ORNAMENTS**

(76) Inventor: **Hunter Owen Pye**, Little Rock, AR
(US)

(**) Term: **14 Years**

(21) Appl. No.: **29/410,411**

(22) Filed: **Mar. 9, 2012**

(51) **LOC (10) Cl.** 11-05

(52) **U.S. Cl.**

USPC **D11/121**

(58) **Field of Classification Search**

USPC D11/117, 121, 124, 125, 131, 132;
428/7, 8, 9, 12, 15

See application file for complete search history.
